UNITED STATES PATENT OFFICE.

LOUIS WULFF, OF PITTSFIELD, MASSACHUSETTS, ASSIGNOR TO GENERAL ELECTRIC COMPANY, A CORPORATION OF NEW YORK.

ELECTRICAL APPARATUS.

1,426,940.

Specification of Letters Patent. Patented Aug. 22, 1922.

Application filed October 13, 1920. Serial No. 416,668.

To all whom it may concern:

Be it known that I, LOUIS WULFF, a citizen of the United States, residing at Pittsfield, county of Berkshire, State of Massachusetts, have invented certain new and useful Improvements in Electrical Apparatus, of which the following is a specification.

My invention relates to electrical apparatus and particularly to apparatus having 10 windings supported about the legs of magnetic cores, such as are employed in transformers, reactances and the like.

The object of my invention is to provide an improved means for retaining the windings in a predetermined spaced relation and which is reliable, safe and readily manufactured.

When assembling windings about the leg of a magnetic core, in the manufacture of 20 electrical apparatus, it is necessary that certain predetermined spaced relations shall be maintained both between the winding groups and between the windings and the core; hence to secure this end, spacing devices having elements placed in both radial and axial directions are relied upon for maintaining the windings in the desired relations.

These spacing elements usually project 30 beyond the edges of the windings themselves and have filling pieces inserted between their ends which take the radial thrust of the windings should they tend to be displaced laterally; such filling pieces abutting 35 against the walls of the insulating cylinders, particularly the inner ones, which are generally concentrically disposed about the winding axis. To make a good alignment of these spacing elements and to make a 40 solid abutment between the windings and insulating cylinders, as heretofore practiced, requires considerable skill and attention on the part of the mechanic assembling the parts.

By my invention, however, these spacing 45 elements are readily and quickly disposed in perfect alignment and do not require the exercise of a high degree of skill on the part of the mechanic to secure this end; 50 moreover a solid abutment is at the same time secured since I make use of an improved aligning and securing means in conjunction with the spacing elements.

For a more complete understanding of the 55 nature and objects of my invention, refer-

ence should be had to the following detailed description taken in connection with the accompanying drawings in which:

Fig. 1 shows an arrangement of windings suitable for transformers provided with 60 spacing elements arranged in accordance with my invention; Figs. 2 and 3 show details in spacing elements as employed in Fig. 1; Figs. 4, 5 and 6 show details of a modified arrangement; Fig. 7 shows a still 65 further modification suitable for the arrangement of Fig. 1; while Figs. 8 to 14 show further details of this modification.

Referring now to Fig. 1 of the drawings, 10 denotes a magnetic core, of any suitable type, on the leg 11 of which are mounted interleaved disc coil windings 12. These windings would be suitably connected as high and low voltage windings where the apparatus embodying my invention is a 70 transformer, this being the type of electrical apparatus to which my invention will have its widest application.

The windings 12 are insulated from the core 11 by the inner insulating cylinder 13, 80 shown as interposed between the core 11 and the windings 12. An outer insulating cylinder 14 is provided to insulate the windings shown on leg 11 from other windings, 85 or from exterior grounds such as the housing which may inclose the apparatus, or from other portions of the core.

The windings, however, are themselves maintained in a predetermined spaced relation, after they have been assembled, by the 90 spacing elements shown at 16 in order that proper ventilation and insulation shall be at all times provided.

The spacing elements 16 may be any one of the forms hereinafter described, those 95 specifically shown in Fig. 1 being U-shaped as more clearly shown in Figs. 2 and 3. In this form the simple U's are slipped over the winding coils and stacked one above the other. To align the spacers 16 a channel-shaped insulating member 17, which may be of molded press-board or hard fiber, is disposed along the backs of the spacers 16 and has its straight upstanding edge members 18 100 engaging with the sides of the U's. To properly space the backs of the U's from the inner insulating cylinder 13, the channel member 17 is provided with one or more insulating fillers 19 as shown.

It is readily seen that the use of a channel 110

member, as shown at 17, at once provides the proper distancing of the coils with a solid abutment between them and the insulating cylinder 13, and at the same time insures perfect alignment of the spacing elements 16.

Instead, however, of a channel member with straight upstanding edge members as shown in Figs. 2 and 3, I may use a channel member of the type shown in Figs. 4 to 6. Here the channel member 20 has inturned edge members 21 which are adapted to engage with transverse recesses or grooves 22 cut in the end portions of spacing elements 23. This arrangement provides an interlocking structure from which the spacing elements cannot be accidentally displaced. The distance denoted a , by which the grooves 22 are disposed from the back ends of spacers, 20 may be any that is desired, but is preferably such as to provide the desired depth of insulating abutment between the coils and the insulating cylinder against which the channel member 20 is disposed. The space between the spacing elements themselves in the channel member is filled by small rectangular fillers 24 which are cut snugly to fill the channel space, a sufficient number of them being inserted at each point exactly to equal 30 the thickness of a coil such as shown at 12' in Fig. 6.

The use of an interlocking channel such as is shown at 20 is particularly advantageous where it is desired to dispense with the outer insulating cylinder, such as I have shown at 14, since such channel ties in the spacers and holds them against lateral displacement in either a radial or tangential direction.

40 All the advantages, however, of a channel with inturned edges may be had from a channel with straight upstanding edges by the use of the construction which I have shown in Figs. 7, 8, 9, etc.

45 In Fig. 7, I have shown a U-shaped channel member 30 with straight upstanding edges 31, which has its top and bottom portions 32 and 33 bent over to properly finish off the device. To get the effect of an inturned edge in connection with the plain U-shaped channel 30, I employ a slotted insulating filler 35, which is clearly shown in perspective in Fig. 8.

The slotted filler 35 comprises two side 55 portions 36 and a bottom or end portion 37. The filler shown in Fig. 8 is made two-ply or of two thicknesses of insulating material, but any desired thickness may be employed; the bottom portion 37 being bent under to 60 fit in the bottom portion 33 of the channel 30, while the top portions 38 of the side portions 36 are likewise bent over to fit into the top portion 32 of the channel. The intermediate parts 39 of the side portions 36 in Figs.

65 7 and 8 are shown as vertically disposed and

serve as a stay to engage with and hold the spacing elements 40 in place, which elements are also provided with transverse recesses or grooves 41 in their end portions spaced a sufficient distance from the end to provide a portion 42 serving as an insulating abutment of the desired depth between the coils 43 and the insulating cylinder against which the back of channel 30 abuts. Fig. 11 shows, in perspective, an element 40 thus formed.

To retain the elements 40 properly spaced apart along the portions 39 of the split filler 35, small T-shaped fillers 44, preferably sufficient in number to have the depth of a coil 43, are inserted in the spaces, indicated at 45 in Fig. 8, which obtain between the protruding ends of elements 40. In this manner a solid back and abutment for the coils is provided which holds the elements 40 in perfect alignment against both radial and tangential displacement.

The filling in the top portion 32 of the channel is made solid by the use of a large T-element 46 which is shown in perspective in Fig. 13. The element 46 is shown as about 90 to be inserted in place in Fig. 7 and actually in place in Fig. 9 which is a top-plan view of the device shown in Fig. 7 with the portion 32 cut away. It will be observed that the tongue of element 46 fits down in 95 between the portions 38 of the split filler 35, the length of the tongue being proportioned to terminate with the ends of filler 35.

Instead of the elements 40 being used to space the coils 43, ventilated elements of the 100 type shown at 50 in Fig. 12 may be employed in the assembly of the device shown in Fig. 7. The element 50 has grooves 51 cut preferably obliquely across its face which are adapted to accommodate the passage of the cooling medium for the coils.

Should it be impractical or for other reasons undesirable to make the combined width of the filler 35, the breadth of ends 42 and the thickness of the channel 30 equal to 110 the desired distance the windings or coils 43 must be spaced from the cylinder abutting the back of channel 30, then the coils 43 may be provided with additional spacing fillers as shown at 55 in Fig. 14. Here a coil 115 43' is wound on a cylindrical filler 55 so that when assembled in place it will snugly fit against the portions 39 and yet provide the desired distance or clearance between coils and insulating cylinder.

Having now described what is at present the best means known to me for carrying out an embodiment of my invention, I would have it understood that such means are merely illustrative, and that I do not mean 125 to be limited thereby to the exact details shown nor restricted in the choice of recognized equivalents except as defined in my claims hereunto appended.

What I claim as new and desire to secure 130

by Letters Patent of the United States, is,—

1. In an electrical apparatus, the combination with windings composed of coils in assembled relation, of spacing means for the windings comprising radially disposed elements, fillers and a channel member, said channel member engaging said elements to secure them against lateral displacement and to hold them in alignment.

10 2. In an electrical apparatus, the combination with windings composed of coils in assembled relation, of spacing means for the windings comprising radially disposed elements, fillers and a channel member, said channel member engaging said elements to secure them against lateral displacement and to hold them in alignment and having said fillers disposed therein to provide a solid abutment for said coils.

20 3. A spacing device for disc-coil electrical windings, said device comprising elements radially disposed among the windings, a channel member securing said elements in alignment and fillers disposed within the 25 channel member to provide a solid backing.

4. A spacing device for disc-coil electrical windings, said device comprising elements radially disposed among the windings, a channel member securing said elements in alignment and fillers disposed within the 30 channel member to provide a solid backing, said channel member being formed to engage said fillers and radial elements to secure them against lateral displacement.

5. A spacing device for disc-coil electrical windings, said device comprising elements radially disposed among the windings, a channel member for securing said elements in alignment and fillers disposed to provide a solid backing in said channel, said channel 40 member having securing members disposed longitudinally of its upstanding edges, and each of said radial elements being provided with transverse grooves near one end and said securing members extending into the 45 grooves of said radial elements to prevent displacement thereof.

In witness whereof, I have hereunto set my hand this 8th day of Oct., 1920.

LOUIS WULFF.
